[57] CLAIM

The ornamental design for a retainer clamp for elongated bodies or the like, as shown and described.

DESCRIPTION

FIG. 1 is a left side elevational view of a retainer clamp for elongated bodies or the like, showing my new design;

FIG. 2 is a front elevational view thereof;

FIG. 3 is a right side elevational view thereof;

FIG. 4 is a top plan view thereof;

FIG. 5 is a bottom plan view thereof;

FIG. 6 is a rear elevational view thereof;

FIG. 7 is a cross-sectional view thereof taken along line VII—VII in FIG. 3.

FIG. 8 is a front top and right side perspective view of the retainer clamp with an inverted second clamp of the same configuration coupled thereupon;

FIG. 9 is a front, top and right side perspective view of the retainer clamp with an inverted second clamp of the same configuration coupled thereupon and rotated 90° from the position shown in FIG. 8; and

FIG. 10 is a bottom and left front perspective view thereof.

FIG. 1
